UNITED STATES PATENT OFFICE.

LYMAN E. WOODARD, OF OWOSSO, MICHIGAN.

CASKET-HANDLE.

SPECIFICATION forming part of Letters Patent No. 530,814, dated December 11, 1894.

Application filed August 22, 1894. Serial No. 520,974. (No model.)

To all whom it may concern:

Be it known that I, LYMAN E. WOODARD, of Owosso, in the county of Shiawassee and State of Michigan, have invented a new and useful Embossed Base or Ear for Casket-Handles, of which the following is a full, clear, and exact description.

My invention relates to an improved device for facilitating the attachment of coffin or burial casket handles to the side walls of such receptacles.

In the manufacture of coffins and caskets for burial purposes it is desirable to construct the walls of such receptacles of wood or metal as thin as is admissible to render them light to handle; and to insure safety in portage, the handles of coffins or caskets must be secured to their side walls in a reliable manner avoiding the formation of excavations or indentations in said walls that would weaken or mar them.

The objects of my present invention are, to provide a novel constructed base support or ear for attachable coffin or casket handles, which will greatly facilitate their connection with the side walls of such receptacles, will avoid the formation of cavities in said walls, be adapted for rapid and cheap production from sheet metal, and that may be quickly and reliably applied to the coffin sides after the latter are covered with cloth or otherwise completely finished, the improvement when in place, affording strong, reliable, ornate ears or embossed base pieces for the handles, that may be of the drop style or be rigidly projected from the coffin as may be preferred.

To these ends my invention consists in the construction and combination of parts, as is hereinafter described and claimed.

Reference is to be had to the accompanying drawings forming a part of this specification, in which similar figures of reference indicate corresponding parts in all the views shown.

Figure 1 is a front view of the improvement in duplicate, and a connected pendent coffin handle on the side of the coffin shown in part. Fig. 2 is a transverse sectional view on the line 2-2 in Fig. 1. Fig. 3 is a transverse sectional view on the line 3-3 in Fig. 2. Fig. 4 is a transverse sectional view of the improvement on a coffin wall shown in part and a plan view of a coffin handle portion, showing

it connected to the coffin by a T-head bolt. Fig. 5 is a transverse sectional view of the improved coffin handle base piece or ear, and a cloth covered handle and its arm partly in section, showing a feature of advantageous adjustment afforded by the improvement; and Fig. 6 is a transverse sectional view of the improvement, a handle bar in part and one bracket arm of the handle secured to a coffin wall in part by a screw eye attachment.

As before mentioned it is desirable to avoid excavations in the side walls of a coffin or casket where the handles are connected thereto, and if drop handles are used and which are preferable, the side walls of the coffin or casket should be reinforced where the handles are attached and means provided for concealing the jointed connection of the handle with the coffin wall, so as to render the attachment neat and shapely in appearance.

The device that is the subject of my present invention, provides an improved ear or embossed base piece for the bracket arms of a coffin handle to impinge and receive support from while in service, and which will receive the knuckle joints of such parts, concealing the hinged connection, and entirely dispensing with the formation of cavities in the sides of a coffin provided with the present improvements.

When the improved ears for the coffin handles are to be attached thereto, the walls of the coffin need only be perforated completely for the insertion of staple bolts or T-headed bolts, that directly connect the coffin handles with the sides of the coffin or casket when these are employed for such a purpose, as has been previously shown in patents granted to me, and numbered 471,047 and 453,572.

The improved ear for coffin handles is most available for service in connection with the folding handle bars shown in the Letters Patent mentioned, and is herein illustrated as a coacting and essential feature for pendent coffin handles constructed substantially similar to those shown in said patents.

In the drawings, 10 represents a portion of the side wall of a coffin or casket, which part may be near the head or foot of the latter, the handles being provided in pairs as usual, one pair being located near each end of the receptacle for its convenient portage.

The handle bar 11 is of a suitable length and near its ends is furnished with two similar bracket arms 12 that are attached one near each end of the bar 11. The other ends 5 of the bracket arms have return bent hooks 12^a formed on them, and as shown the hooked portion of each arm is reduced in size, thereby affording a peripheral shoulder 12^b, the portion of the arm nearest to said shoulder being rounded on its surface so as to give it the form of a spherical segment which has its center in the bow of the hook 12^a.

The improved base piece or ear, that is furnished for each bracket arm 12, consists essentially of a deeply dished sheet metal disk 13, that may have an oblong shape as represented in Fig. 1 or be given any other desired conformation of its edge portion. Each disk 13 is flanged at its edge to produce a cavity 20 of a suitable depth, the portion bounded by said flanged edge being left flat and centrally apertured in circular form.

The hook members 12^a of the bracket arms 12 are made freely insertible through the center holes of the ears 13 until the shoulders 12^b impinge the marginal portions of the ears that bound their perforations.

It is of special advantage in manufacturing the ears 13 that they be produced from sheet metal, by cutting and forming them with dies of a correct shape on a suitable machine, as this permits the rapid and perfect formation of the ears complete in large quantity at a low cost. As the sheet metal ears 35 13 alone are not sufficiently strong to sustain the imposed weight of a coffin or casket and its contents, it is necessary to provide a backing piece for each ear. For this purpose it is preferred to employ a washer 14 40 that may be formed of wood or other available material, said washer being centrally apertured to form a receptacle for the joint connection of the bracket arm with the side of the coffin, the thickness of the washer and 45 its outer diameter being so proportioned that said part will have an assured contact with the inner surface of the sheet metal ear 13 when the latter is with the washer in it, imposed on the side wall of a casket or coffin 50 and thereto secured.

The manner of applying the improvement to a coffin side wall along with the handle bar and its bracket arms is as follows: The sheet metal ear 13, provided for each bracket arm 55 12, is secured along with its supporting washer 14 to the side wall of the coffin 10 at a proper distance from the ends of the coffin, by a single screw 15 that is loosely introduced through a perforation in the ear, made 60 at an appropriate point, and also through an aligned perforation in washer 14 that is in place within the ear, the washer being so located that its aperture will register with the aperture in the ear, and thus produce a cavity 65 between the ear and wall of the coffin to which the ear 13 and washer 14 are secured by the screw 15, as is represented in Figs. 2

and 5. The attachment of the ears and their reinforcing washers as stated, clamps each pair of ears at a proper distance apart on the 70 coffin wall, for the reception of the hooked ends of two bracket arms for an attachment of the handle bar whereon said arms are affixed, and as is shown the hooked end of each arm may be introduced within the aligned 75 holes in the ear and washer.

To directly hinge the bracket arms 12 on the coffin wall, staple shaped bolts 16 or T bolts 17 may be employed, and as shown, the double or single limbs of such bolts when 80 passed through properly located perforations in the coffin wall and secured thereto by washers and nuts 18, will be adapted for a hinged engagement of their inner end portions with the hooked ends of the bracket 85 arms, which will permit the latter to receive a rocking movement sufficient to project said arms at a proper angle from the coffin wall, or hang pendent from the ears 13. Preferably, in this case, the hinged connection of 90 the bracket arms 12 with the coffin wall is effected by bolts 19 having a ring eye 19^a formed on the inner end, the body of the bolt being threaded to receive a nut and washer 20, as shown in Fig. 6, the hooks on the inner 95 ends of the bracket arms being inserted through the ring eyes so as to produce hinge joints, thus affording a neat, cheap and reliable jointed connection of the arms of the handlebars with the walls of a coffin or casket. 100

Frequently, coffins are covered with cloth fabric as a means of appropriately finishing their exteriors, and the handles with their bracket arms are also covered with a suitable colored fibrous fabric to suit the finish of the 105 coffin.

Sometimes the thickness of cloth preferred to cover a particular coffin or casket, may be greater than that ordinarily used, and as it is desirable to cover the knuckle joint portions of the bracket arms, increased space at the upper edges of the apertures in the centers of the ears 13 must be provided, to accommodate the thicker material and afford room for the proper rocking movement of the 115 bracket arms.

In the formation of the movable ears for the coffin handles, as hereinbefore explained, cloth of various thicknesses may be used to cover the handle bars and their arms, without 120 enlargement of the diameter of the apertures in the ears and their reinforcing washers.

Referring to Fig. 5 it will be seen that by slightly changing the position of the screws 15, so as to correspondingly raise the ears 13 125 and washers 14, increased width is afforded the annular openings at the tops of the knuckle joints on the bracket arms, so that thicker material that is affixed to the rounded exteriors of said joints, will be permitted to move 130 along with the arms in said spaces without touching the edges of the apertures in the ears.

Should the covering material for the arms

12 be quite thin, and it is desired in order to produce a neat finish that the knuckles on the joints of said arms should work close to the upper edges of the apertures in the ears, 5 this can be effected by lowering the ears with regard to the position of the joint bolts, which will diminish the distance between the centers of the hinge joints and top edges of the circular apertures in the ears, and so locate 10 said edge portions nearer the knuckle joints.

It is claimed for this improved coffin or casket ear, that it greatly facilitates the attachment of pendent handle bars to the side walls of such structures, and affords a strong, 15 neat and concealed connection of the handle arms therewith, which will permit the handle bars to hang pendent, or be lifted into a horizontal position as is indicated in Figs. 3 and 5.

The impinge of the shoulders of the handle 20 bar arms on the reinforced edges of the apertures in the ears 13 limits the upward rocking movement of the arms and handle bars, so that said ears receive the weight of the coffin and its contents and coact with the hinge joints of 25 the arms to sustain such weight when the coffin or casket is carried by its handles.

Having thus described my invention, I claim as new and desire to secure by Letters Patent—

30 1. In casket handle attachments, a sheet metal disk having an opening, and a separate washer reinforcing the disk at its opening, substantially as described.

35 2. In casket handle attachments, the combination with a disk having an opening, and a washer adapted to reinforce the disk at its opening, of a bolt entering the washer aper-

ture, and an arm connectible with the bolt, substantially as described.

3. The combination with the wall of a cas- 40 ket, of a recessed and perforated ear, a washer in the recess, impinging the casket wall and said ear, and means for securing the ear and washer to the casket wall, substantially as de- scribed.

4. The combination with the wall of a cas- 45 ket, a recessed and perforated ear attached thereto, a washer in the recess in the ear and impinging on the casket wall and ear, and a screw securing the washer and ear on the 50 casket wall with the apertures in said wall and ear in alignment, of an arm having a hooked end adapted to enter the aperture in the ear and washer, and a ring eye bolt se- cured in the casket wall and engaged by the 55 hooked end of the arm, substantially as de- scribed.

5. The combination with the wall of a cof- 60 fin, and a handle bar having arms provided with hooked ends and peripheral shoulders at the bases of said hooked ends, of hinge bolts securable in the coffin wall and loosely en- gaging the hooked ends of the arms, sheet 65 metal ears apertured to receive the hooked ends of the arms and receive the impinge of the shoulders on said arms, reinforcing wash- 70 ers within the ears, impinging the wall of the coffin and said ears, and means to changeably secure the ears and the reinforcing washers on the coffin wall, substantially as described.
